TRAFFIC INSTRUCTIONAL MEANS FOR INCORPORATION IN AND USE WITH ELECTRIC TRAFFIC SIGNAL LIGHTS

Frank A. Davis, Box 115, Flat Rock, Ind., and Herold H. Losche, 541 Euclid Ave., Greenwood, Ind.
Filed May 22, 1963, Ser. No. 282,302
12 Claims. (Cl. 340—107)

This invention relates to electric traffic signal lights and more particularly to means for providing traffic instruction on the lenses of the "stop," "go," and "caution" lights of the normal electric traffic signal lights used at street or road intersections in addition to the color directions of the signal.

The commonly used and ordinarily recognized electric traffic signal lights, known throughout the nation, direct motorists by color code when to "stop," "go," and use "caution" or prepare to stop. Sidewalks and curbs are often strewn with additional traffic instructions on signs to notify motorists—and pedestrians—of speed limits, school zones, right turns at certain times, etc. It is also recognized that conditions may be quite different for different hours of the day and traffic engineers would like to change the traffic pattern, including speed, to meet these changing conditions for better or safer flow of traffic. These changing conditions are only prepared for, if at all, by curb or sidewalk signs which are also oftentimes obscured by heavy traffic or by other obstructions which cause motorists to miss seeing the signs. Also, the curb or sidewalk signs of instructions to the motorists set up hazardous conditions for that reason that the motorists need most of their attention on moving traffic and pedestrians rather than to be distracted in an eye-search for the instructional signs.

The present invention was conceived to remove many of the disadvantages of the many instructional signs for the motorists by placing these instructions in the traffic light itself where the motorists must look for "stop," "go," and "caution" color directions. For the purpose of clarity herein traffic "directions" will be referred to as those provided by the color coded traffic signal of "stop," "go," and "caution" while all other traffic information will be referred to as "instructions." This invention further contemplates the changes in instructions for different times of day. For example, the speed limit for city traffic is usually fixed and well publicized so that curb and sidewalk signs should be unnecessary, but in certain areas, where traffic is exceptionally heavy or there is a school, it may be desirable to slow down the motoring traffic. Such traffic instructions could be, by this invention, given by the green or "go" signal at the traffic intersection. The same timing mechanism that times the traffic signal could be used, or readily adapted, to superimpose the additional traffic instructions on the face of the green or "go" signal, such as "20 m.p.h.," an arrow instructing all traffic to go right, etc. In this invention means are shown and described to acutate a flag, panel, or curtain over the face of the traffic signal light, preferably the green or "go" signal light, although the yellow "caution" or red "stop" lights could be used where appropriate, with written instructions thereon. These instructions may be in symbol form, such as arrows showing the direction that traffic must take, speed limits abbreviated, or school notice with a speed limit. The flag, panel, or curtain is actuated by an electric motor, such as a solenoid

2

or rotary motor, in circuit with the timing mechanism of the traffic signal. The timing mechanisms are usually synchronous clock motors which drive the electric switches of the traffic signal. Electric switches could be readily added to cause the motor actuator of the flag, panel, or curtain to be superimposed over the preferred light of the traffic signal light at predetermined hours. This puts all the important traffic information before the motorist who, needless to say, must watch the traffic signal for proper operation of his vehicle. It is therefore a general object of this invention to provide the presently used and operated electric traffic signals with traffic instructional flags, panels, or curtains operative in conjunction with the timing mechanism of the electric traffic signal, to additionally instruct motorists as to a traffic regulation along with the red "stop," yellow "caution," or green "go" color directions of the signal.

These and other objects, advantages, features, and uses of this invention will become more apparent to those skilled in the art as the detailed description proceeds when considered along with the drawings, in which:

FIGURE 1 illustrates a common electric traffic signal with an instructional flag or panel superimposed over the lens of the green or "go" signal;

FIGURE 2 illustrates a side view of the FIGURE 1 view, or 90 degrees of the FIGURE 1 view, to show the external solenoid operators;

FIGURE 3 is an enlarged view of the flag or panel and operator of FIGURES 1 and 2 with the traffic signal housing shown broken away;

FIGURE 4 illustrates an enlarged view of a flag or panel having a traffic instruction thereon;

FIGURE 5 illustrates a means for operating three different flags or panels at different hours by rotary electric motors;

FIGURE 6 illustrates the use of paired internal flags or panels motorized by a rotary electric motor;

FIGURES 7 and 8 illustrate different types of paired flags or panels and different traffic instructions for internal use in the traffic light housings as shown in FIGURE 6;

FIGURES 9 and 10 illustrate a modification of hinged flags or panels that could be used internally of a traffic signal housing and the motive means therefor;

FIGURE 11 shows a face view of the hinged flag or panel used in FIGURES 9 and 10; and

FIGURES 12 and 13 illustrate a further modification of a curtain type flag or panel, FIGURE 12 showing the flag or panel in operative display position while FIGURE 13 shows the flag or panel in the inoperative or non-display position.

Referring more particularly to FIGURES 1, 2, and 3, there is shown in FIGURE 1 one face view of an electric traffic signal having four faces for a cross street intersection. The traffic signal 20 is supported by a steel post 21, shown broken away for illustrative purposes, although some are suspended by cables or other means in actual practice. The signal has the usual three vertical lights, the upper of which is with a red lens 22 for "stop" signalling, a middle yellow "caution" lens 23 for caution signalling, and a lower green lens 24 for "go" signalling. On the lower green lens 24 is a flag or panel 25 of opaque or slightly transparent material, such as plastic or metal, with a transparent or cut-out portion of straight up and right arrows 26. FIGURE 2 shows a view of FIGURE 1 turned 90 degrees. FIGURE 3 illustrates an enlarged sectional view of the traffic signal of FIGURES 1 and 2

more clearly showing the flag or panel 25 and the instructional traffic symbol 26 thereon. The flag or panel 25 is hinged at the top 27 with shaft ends being journaled in bearing caps 28. The shaft hinge connected to the flag or panel 25 extends through the left bearing cap 28 to which end is fastened a lever arm 29. This lever arm is linked by 30 to the plunger of a solenoid 31, the solenoid coil 32 being fastened in any suitable manner to the frame of the traffic signal. The solenoid coil has leads 33 that may be connected to the traffic signal timing mechanism to actuate the flag or panel down over the green lens 24 at designated times of the day. The solenoid is of the type having a spring 34 therein to bias the plunger 31 outwardly in the unenergized condition to raise the flag or panel 25, as shown in FIGURE 2, or it may be of the locking type which will remain in either of its two positions. The particular traffic instruction shown, when the solenoid 32 is energized and the flag 25 is down, is that traffic may only go straight through or to the right. With the flag 25 up it functions as a hood over the green lens. It may be presumed that traffic may normally flow left, right, and straight through with the flag 25 up. It may be readily understood that the timing mechanism could be set to change the traffic pattern two, three, or more times during the day to suit conditions.

FIGURE 4 shows a flag or panel only, which may be used in the FIGURES 1, 2, or 3 examples, to change the speed limit during certain times of the day, for example, from a 40 m.p.h. speed limit to a 30 m.p.h. speed limit as shown in the figure. FIGURE 5 shows still another flag or panel traffic instructional sign, that of a curve, which indicates that traffic may only go to the right at a Y intersection during the hours that the flag is covering the green lens of the traffic signal. FIGURE 5 also illustrates that as many as three flags or panels, giving three different instructions, at different times of the day, may be used. The flag or panel 25 is shown in the effective display position, while the flags or panels 25a and 25b are shown in the ineffective or non-display positions. Further, FIGURE 5 shows the flags actuatable by rotary electric motors 40 with worm gears 41 in engagement with pinion gears on the flag or panel shafts. Each motor 40 will be wired to the timing mechanism of the traffic signal for sequential operation at different times of the day as necessity requires.

FIGURES 6, 7, and 8 illustrate another modification of the flag or panel traffic instruction which may be used, preferably inside the traffic signal housing. In this modification, the flag or panel is in two pieces and operated as two oppositely hinged paired doors 45, 45 and 46, 46. When the paired flags or panels are operated to be in alignment in the beam of the green lens of the traffic signal, their adjacent edges touch or lap to provide the traffic instruction, as shown in FIGURES 7 and 8. In this modification, one electric rotary motor 47 is used to operate the paired panels or flags 45 and 46 on opposite faces of the green lens through shafts 48 and worm gears 49 cooperating with small pinion gears on the flag or panel shaft hinges, as well understood by those skilled in the art. The signal lights and reflectors 50 can readily be positioned to allow clearance for the paired flags or panels 45 and 46.

FIGURES 9, 10, and 11 illustrate another modification of the invention, still carrying out the fundamental concept of providing traffic instruction to the motorists, or others involved, in addition to the "stop," "go," and "caution" directions in color. In this modification, the flag or panel is separated into two hinged half-sections 55-56 and 57-58 to decrease the operating space from the space required by the earlier modifications. The four sections of flags or panels, 55-58, are pivoted at their outer top corners 59, 60, 61, and 62, the pivots 59 and 62 being to bearing supports 63 and 64, respectively, for a screw threaded actuator shaft 65. The pivots 60 and 61 are pivoted, respectively, to two travelling blocks 66 and

67 which are threadedly journaled on the shaft 65. The threaded shaft 65 is oppositely threaded over each half section so that rotation in one rotative direction causes the blocks 66 and 67 to travel away from each other, and when the shaft 65 is rotated in the other rotative direction, the blocks 66 and 67 will travel toward each other. Limit switches 68 and 69 break the motor circuit for each rotative direction as the panels or flags reach the fully open non-display or fully closed display positions. As illustrated in FIGURE 9, a reversible rotary electric motor 70 drives a pinion 71 on the threaded shaft 65 by a worm gear on the motor shaft, shown and described for the other figures. FIGURE 9 also shows the reflector 72 and light bulb 73 in position. FIGURE 11 shows a face view with the sectioned flags or panels in closed display position over the green lens of the traffic signal with the traffic symbol instruction thereon indicating that only straight through traffic or left turn traffic may proceed when the green light is illuminated. It is also to be understood that the motor 70 is circuited through the limit switches to the timing mechanism of the traffic signal as disclosed for the preceding figures.

FIGURES 12 and 13 illustrate a still further modification of a curtain type of flag or panel 80 to be pulled over the face, or back side, of the green lens of the traffic light. The curtain 80 may be of a slightly transparent or opaque material with a transparent or cut-out portion 81 of figures or letters giving traffic instructions. The curtain 80 is rollable upon a window-blind type roller 82 that is normally spring biased to roll the curtain 80 thereon, and without any catches as found in window-blinds. The curtain 80 has a cord or other suitable means 83 looped from each outer corner, the mid portion being fastened in any suitable manner to the mid-point of a second roller 85 journaled in bearings 86. The roller 82 is likewise journaled in bearings 87, the bearings 86 and 87 being supported on the housing of the traffic signal (not shown) as by bolts or in any other suitable manner. The roller 85 has a shaft extension thereon with a small pinion gear that is in mesh with the worm gear 88 of an electric rotary motor 89. The motor 89 is energizable through the timing mechanism of the traffic signal in the same manner as described for the prior figures. Limit switches could be positioned in any suitable manner to limit curtain travel in each direction, as well understood by those skilled in the art. FIGURE 12 shows the curtain 80 unrolled to expose or display the traffic instruction from the green lens 90, while FIGURE 13 shows the curtain 80 rolled up to expose the whole green lens 90 and non-display of the traffic instruction. The cord 83 in the rolling and unrolling operation, by virtue of its central attachment to the roller 85, will not cross cords to foul the operation.

It is to be understood that the traffic instructions shown on the various figures are for example only herein and that any designation, symbol, figure or figures, letter or letters, and words may be used on the variously used flags, panels, or curtains as deemed appropriate or necessary in carrying out the inventive concept. By these means traffic instructions, in addition to the "stop," "go," and "caution" color directions, can be communicated to the drivers of vehicles and pedestrians alike which will eliminate the necessity of looking two or more places for traffic regulations in the area.

While many modifications and changes may be made in the constructional details and features of this invention, as illustrated in the preferred embodiments herein, in the actual practice of the inventive concept herein, it is to be understood that we desire to be limited only in the spirit and scope of the appended claims.

We claim:

1. A traffic instructional means for an electric traffic light signal in addition to "stop," "go," and "caution" traffic light directions, comprising:

traffic instructional unit means having a substantially

light impervious portion around a traffic instruction and of at least as great an area as the traffic light beam and transparent portions constituting the traffic instruction therein, said traffic instructional unit means being attached to said electric traffic light signal for interposition in the light beam of selected lights of said electric traffic light signal for display of the traffic instructions therein along with said traffic directions and for retraction of said traffic instructional unit means from display within said light beam of the selected lights of said traffic light signal to allow display of said traffic directions alone;

5
motive means mechanically coupled to said traffic instructional unit means for driving said traffic instructional unit means into display and non-display position; and

means electrically coupling said motive means to a timing means to time the effective display time that said traffic instructional unit means is interposed in the traffic light beam and non-display time that said traffic instructional unit means is out of the traffic light beam whereby traffic instructions, in addition to said traffic directions, are effective when said traffic instructional means are in display position.

25
2. A timed traffic instructional means for an electric traffic light signal in addition to the "stop," "go," and "caution" traffic light directions, comprising:

rigid panels each having a substantially light impervious portion and transparent portions designating traffic 30
instructions thereon, each of said rigid panels being hingedly attached to said electric traffic light signal and actuatable into and out of the path of the traffic direction lights for display and non-display positions, respectively, of said traffic instructions;

electric motive means for actuating said panels to 35
said display and non-display that said traffic instructional means is interposed in the traffic light beam position that said traffic instructional means is out of the traffic light beam; and

electric timing means coupled to said electric motive means to time the effective periods of display and non-display of said traffic instructions whereby traffic instructions are displayed when said panels are actuated to the display position in addition to said 45
traffic directions by the traffic lights in whose beams said traffic instructions are interposed.

3. A timed traffic instructional means as set forth in claim 2 wherein

said electric timing means are incorporated in the timing mechanism of said electric traffic light signal.

4. A timed traffic instructional means as set forth in claim 3 wherein

said panels are in plurality for each light beam of a single traffic direction light and actuatable into display position in sequence whereby traffic instructions for different sequential periods are effective.

5. A timed traffic instructional means set forth in claim 4 wherein

said hinged attachments of said panels to said electric 60
traffic light signal are each a shaft fixed to a panel and journaled on said electric traffic light signal housing with a gear on said shaft; and

said electric motive means are electric rotary motors, each having a gear on its shaft in mesh with one each of said gears on said shafts fixed to a panel, whereby each motor is operative to actuate its associated panel and said motors are operative to be energized in a predetermined sequence.

6. A timed traffic instructional means as set forth in 70
claim 2 wherein

said electric timing means is incorporated in the timing mechanism of said electric traffic light signal;

said hinged attachments of said panels to said electric 75
traffic light signal are each a shaft fixed to a panel

and journaled on said electric traffic light signal housing with a lever affixed on each shaft; and said electric motive means are solenoids having the plunger thereof pivotally coupled to each shaft lever fixed to a panel, whereby each solenoid is operative to actuate each associated panel and said solenoids are operative to be energized in sequence.

7. A traffic instructional means for an electric traffic light signal in addition to the "stop," "go," and "caution" traffic light directions, comprising:

pairs of foldable panels, each pair having a substantially light impervious portion and transparent portions therein designating traffic instructions, and each pair being pivotally suspended from the top outer corners thereof to journal blocks, the outermost journal blocks being supported within the housing of the electric traffic light signal above the "go" light; a shaft journaled in the two outermost journal blocks, said shaft having a gear wheel centrally thereof and oppositely threaded on opposite half portions, each opposite threaded half portion thereof having the other journal blocks threaded journalized thereon to cause said other journal blocks to travel toward and away from each other as said shaft is rotated in either of its two rotative directions thereby folding and unfolding said foldable panels for display and non-display positions, respectively, of said traffic instructions;

rotary motor means having a gear on the shaft thereof in mesh with the gear wheel of said shaft to rotate said shaft in its two rotative directions; and

circuit timing means coupled to said rotary motor for energization at prescribed timed intervals to drive said foldable panels into said display and non-display positions whereby each "go" direction of said electric traffic light signal will also display an additional traffic instruction when said foldable panels are driven to the display position.

8. A timed electric traffic instructional means as set forth in claim 7 wherein

40
said circuit timing means is incorporated in the timing mechanism of said electric traffic signal to time the display and non-display periods of the traffic instructions during the day.

9. A timed electric traffic instructional means as set forth in claim 8 wherein

said circuit timing means include limit switches in the circuit thereof actuatable by said traveling blocks to break the circuit to said rotary motor at each limit of travel of the traveling journaled blocks along said threaded shaft.

10. A timed traffic instructional means for an electric traffic light signal in addition to the "stop," "go," and "caution" traffic light directions, comprising:

a curtain of substantially light impervious material having transparent portions therein designating traffic instructions, said curtain being biased to rolled-up position on a roller supported within the housing of said electric traffic light signal adjacent to path of a traffic light beam;

a second roller driven in reversible rotational directions by an electric motor, said second roller having cord means attached thereto and to said curtain to cause said curtain to be unrolled to a display position and to be allowed to return to said rolled-up non-display position to effect the display of traffic instructions and the non-display thereof, respectively; and

timing means circuited to said electric motor to time the display and non-display periods of said traffic instructions whereby traffic instructions are displayed during prescribed periods in addition to the traffic directions of the electric traffic light signal.

11. A timed traffic instructional means as set forth in claim 10 wherein

said timing means is incorporated in the timing mechanism of said electric traffic light signal.

12. A timed traffic instructional means as set forth in claim 11 wherein said second roller has a gear wheel thereon in mesh 5 with a gear on the shaft of said electric motor to drive said second roller in reversible rotational directions.
